SQUEEZER EXTRACTOR WASHING
MACHINE

Robert R. Candor, Oakwood, Ohio, assignor to
General Motors Corporation, Dayton, Ohio, a
corporation of Delaware

Application March 25, 1948, Serial No. 17,053

7 Claims. (Cl. 68—21)

1

This invention relates to domestic appliances and more particularly to washing machines.

An object of this invention is to provide a washing machine in which the tub is oscillated and is provided with a flexible diaphragm at the top, together with means to impart a vacuum to the tub below the diaphragm for the purpose of wringing water out of the clothes after they have been washed.

Another object of this invention is to provide a washing machine of the character described in the foregoing paragraph, in which a washing cycle, together with one or more rinse cycles may be performed automatically.

Another object of this invention is to provide a washing machine in which the tub is oscillated and is provided with a flexible diaphragm near the top, together with means to impart a vacuum to the tub below the diaphragm and with means to hold the diaphragm in its upper position during the time that a vacuum is not imparted to the tub below the diaphragm.

Further objects and advantages of the present invention will be apparent from the following description, reference being had to the accompanying drawings, wherein a preferred form of the present invention is clearly shown.

In the drawings:

Fig. 1 is a vertical cross-sectional view, somewhat diagrammatic, of a washing machine embodying features of my invention; and

Fig. 2 is a cross-sectional view taken along the line 2—2 of Fig. 1.

A washing machine embodying features of this invention may include a tub 10 which is provided with agitating vanes 11. The tub is oscillatable by means of a supporting shaft 12 carried in bearing 13. Means to oscillate the tub may also include a crank 14, connecting rod 15, gearing 16 and 17, and a motor 18.

A flexible diaphragm 19 is provided near the top of the tub. Preferably it is carried by a cover 20, which is hinged at 21 to the tub 10. The diaphragm 19 may, if desired, have its own rigid flange 22, which may rest on the tub flange 23 and which may be clamped downwardly by the flange 24 of the cover 20. However, in the preferred embodiment, the flange 22 is secured by vulcanizing, bolting, or the like to the flange 24. The cover 20 may be provided with a latch and handle 25 for raising the same and for latching it to the tub 10.

Means to impart a vacuum to the tub below the diaphragm 19 are provided. This may take the form of a screen 26 under which a sump 27

2

is formed, which is connected to a flexible, non-collapsible pipe 28, having a coiled portion 29. This pipe is connected to a solenoid multiple valve 30. The valve 30 is connected by pipe 31 to a vacuum pump 32, which may have its own motor, and which discharges through the pipe 33 into a sump or the like. When the valve 30 is properly energized to connect the pipe 27 to the pipe 31, together with simultaneous energization of the vacuum pump, a vacuum is imparted to the tub 10.

Means are provided to hold the diaphragm 19 in raised position during the time that the vacuum is not imparted to the tub below the diaphragm. This may take the form of a flexible, non-collapsible pipe 34, having a coiled portion 35 and a connecting portion 36 leading to the multiple valve 30. The multiple valve 30 may be suitably energized to connect the pipe 31 with the pipe 34 at the time that the pipe 28 is disconnected from the pipe 31. Under these conditions a vacuum is imparted to the space 37, which causes the diaphragm 19 to be held in raised position. At the same time a solenoid valve 38, in the flexible, non-collapsible, overflow pipe 39 having a coiled portion 40, is opened to allow air to enter, or water to be discharged from the tub 10. The atmospheric pressure in the tub 10 causes the raising of the diaphragm 19 when a vacuum is imparted to the space 37. The solenoid valve 38 preferably is of the type which is open except when electrically energized.

Liquid introducing means may be provided for the tub. This may take the form of a solenoid 35 and thermostatic valve 41, which may be connected to a hot water supply 42 and a cold water supply 43. It may discharge through the pipe 44 into the multiple valve 30. At the appropriate time, the valve 30 connects the pipe 44 with the pipe 28, and the solenoid valve 41 is opened to connect either or both the pipes 42 and 43. This causes water to be delivered into the tub through the pipe 28. The valve 41 may include a constant pressure and constant discharge construction such that water at a substantially constant flow is delivered to the tub 10.

If desired, the valve 41 may discharge by a flexible pipe directly into tub 10 without being connected to valve 30.

A timer 50 may be provided to control various elements of the washing machine. The timer 50 may be connected to electrical power source 51. It is connected by lines in the cables 52 with the motor 18, pump 32, and valves 30, 38 and 41. The timer 50 is constructed to send proper im-

pulses to these elements in order to produce the sequences hereinafter more fully described. The construction of the timer and the method of control of the elements are well known, and therefore are not further described.

In the operation of the machine, the timer handle 53 is moved to the start position. This energizes the timer motor and starts it actuating suitable contacts. The steps are as follows:

(a) Clothes and detergent are placed in tub 10. The tub is filled, while a vacuum is imparted to the space 37. For this purpose the valves 30 and 41 are energized to connect either or both the pipes 42 and 43 with the pipe 27, thus introducing liquid at a constant rate into the tub 10 for a predetermined period of time. This fills the tub to the desired level. It is to be understood that any other well known method of filling the tub to the desired level may be used, such as a float control or a pressure responsive switch. At the same time, the valve 30 connects the pipe 34 with the pump 32, and the pump 32 is energized. This imparts a vacuum to the space 37. At the same time the valve 38 is maintained open, preferably by remaining deenergized.

(b) The tub 10 is oscillated after it is filled, and may, if desired, be oscillated while it is being filled. For this purpose the timer 50 sends current to the motor 16 at the desired time, thus causing rotation of the gears to impart oscillation to the tub 10. During this time the vacuum is maintained in the space 37.

(c) Water is withdrawn from the tube 10, a vacuum is imparted to the space 54 below the diaphragm 19, and the vacuum is broken in the space 37. To accomplish this, the timer sends proper impulses to the valves 30 and 38 and to the pump 32. The valve 38 is closed, and the valve 30 connects the pipe 31 with the pipe 28 and the atmospheric pipe 55 with the pipe 36. This causes the water first to be withdrawn from this space. At the same time the vacuum is broken in the space 37 by air passing from the atmosphere through pipe 55, valve 30, pipes 36, 35 and 34, into the space 37. Since the valve 38 is closed at this time, a vacuum is thus imparted to the space 54, within the tub 10, which causes the diaphragm 19 to press down on the clothes and wring them, causing any remaining water soaked in them to flow through the pipe 28 to the pump 32, from which all water and/or air is discharged through the pipe 33.

(d) To rinse the clothes one or more times, steps (a), (b) and (c) are automatically repeated by the timer 50 one or more times, without the addition of detergent.

Reference is made to my prior copending application S. N. 5,320, filed January 30, 1948, patented August 4, 1953, No. 2,647,385.

While the form of embodiment of the invention as herein disclosed, constitutes a preferred form, it is to be understood that other forms might be adopted, as may come within the scope of the claims which follow.

What is claimed is as follows:

1. A washing machine comprising: a tub; oscillating means for said tub; a cover for said tub; a flexible diaphragm carried by said cover and movable into said tub; means to introduce washing liquid into said tub below said diaphragm; vacuum means to impart a vacuum to the space between said cover and diaphragm and subsequently to break said vacuum and to impart a vacuum to the space in said tub below said diaphragm.

2. A washing machine comprising: a tub; liquid introducing means for said tub; oscillating means for said tub; a cover for said tub; a flexible diaphragm at the upper end of said tub and removable therefrom; vacuum means to impart a vacuum to the space between said cover and diaphragm and subsequently to break said vacuum and to impart a vacuum to the space in said tub below said diaphragm, and a timer automatically controlling said liquid introducing means, oscillating means and vacuum means.

3. A washing machine comprising: a vertically disposed tub having an opening for the insertion and removal of clothes; oscillating means for oscillating said tub about a vertical axis; a flexible diaphragm having movable means for securing its working periphery to the rim of said opening and movable into said tub; an agitating vane construction in said tub; a wash water drain substantially at the bottom of said tub; a vacuum pump; and a flexible conduit connected to said drain and vacuum pump.

4. A washing machine comprising: a vertically disposed tub having an opening for the insertion and removal of clothes; oscillating means for oscillating said tub about a vertical axis; a flexible diaphragm having movable means for securing its working periphery to the rim of said opening and movable into said tub; means normally to maintain said diaphragm in its upper position except when a vacuum is imparted to said tub; an agitating vane construction in said tub; a wash-water drain substantially at the bottom of said tub; a vacuum pump; and a flexible conduit connected to said drain and vacuum pump.

5. A washing machine comprising: a vertically disposed tub; oscillating means for oscillating said tub about a vertical axis; a cover for said tub; a flexible diaphragm secured to said cover and movable into said tub; agitating vanes in said tub; a wash water drain substantially at the bottom of said tub; a multiple valve connected to said drain; a water supply conduit, a pump, and a conduit to the upper side of said diaphragm connected to said multiple valve; and control means for said multiple valve and oscillating means to introduce washing liquid into said tub, oscillate said tub and impart a vacuum above said diaphragm during a washing period, to withdraw said washing liquid, and to impart a vacuum to said tub below said diaphragm during a wringing period.

6. A washing machine comprising: a tub having an opening at the top for the insertion and removal of clothes; agitating means secured in the interior of said tub; bearing means supporting said tub for oscillation about a substantially vertical axis; oscillating means secured to oscillate said tub; flexible fluid flow means connected substantially at the bottom of said tub; a flexible diaphragm having its working periphery rigidly and movably connected to said opening; and a stationary fluid translating device connected to said fluid flow means to collapse said diaphragm downwardly against said clothes.

7. A washing machine comprising: a tub having an opening at one end for the insertion and removal of clothes, agitating means secured in the interior of said tub; bearing means supporting said tub for movement about an axis; driving means connected to move said tub about said axis; flexible fluid flow means connected to a lower portion of said tub; a flexible diaphragm having its working periphery rigidly and mov-

5

ably connected to said opening; and a stationary fluid translating device connected to said flexible fluid flow means to collapse said diaphragm inwardly into said tub against said clothes.
